pany, St. Louis, Mo.

Original application May 5, 1945, Serial No.
592,131. Divided and this application October
21, 1949, Serial No. 122,818

1 Claim. (Cl. 102—74)

1

This invention relates to sheathed bodies, particularly sheathed fuzes such as are attached to projectiles, and sheaths therefor.

This application is a division of my copending application for Fuze, Serial No. 592,131, filed May 5, 1945, now Patent 2,564,797, dated August 21, 1951.

The invention particularly pertains to a fuze of a type comprising a fuze body, adapted for application to a projectile, containing a detonating charge and mechanism whereby the fuze may be set for point detonation, or left unarmed for base detonation of the projectile. This mechanism includes a selector in the fuze body which is accessible through an opening in the side of the body and operable by a tool inserted into the opening. To protect the detonating charge and the mechanism within the fuze body until the time of use, the fuze body is provided with a sheath of this invention, the sheath hermetically sealing the fuze, covering the opening in the fuze body through which the selector is accessible (and other openings in the body). To allow for readily setting the fuze for point detonation, without requiring removal of the sheath, the portion of the sheath which covers the access opening in the fuze body is indented and made of such reduced thickness that it may be readily punctured by the tool for manipulating the selector. Thus, while the fuze is hermetically sealed by the sheath, the fuze may be quickly and efficiently set for point detonation without any necessity for removing the sheath. It will be understood that while the invention is particularly applicable to fuzes, as herein disclosed, it is applicable to devices other than fuzes where hermetic sealing with ready access of a tool to the interior of the device for manipulating a mechanism may be desired. Other features will be in part apparent and in part pointed out herein-after.

The invention accordingly comprises the elements and combinations of elements, features of construction, and arrangements of parts which will be exemplified in the structures hereinafter described, and the scope of the application of which will be indicated in the following claim.

In the accompanying drawings, in which one of various possible embodiments of the invention is illustrated,

Fig. 1 is a longitudinal section of a sheathed fuze embodying the invention, the fuze being shown in an unarmed or safe condition of its parts;

Fig. 2 is a view similar to Fig. 1 showing in

2

solid lines the parts in armed condition during flight after having been set for point detonation, and showing in dotted lines a firing condition;

Fig. 3 is a right-end view of Fig. 1 with the fuze sheath or cover removed;

Fig. 4 is a cross section of the sheath or cover before application to the fuze;

Fig. 5 is an oblique elevation viewed from line 5—5 adjacent to Fig. 1, but viewed with the point of the fuze up;

Fig. 6 is a fragmentary cross section taken on line 6—6 of Fig. 1;

Fig. 7 is a fragmentary view taken on line 7—7 of Fig. 3 with internal parts removed;

Fig. 8 is a detail plan view of a selector cup;

Fig. 9 is a side elevation of said cup viewed from line 9—9 of Fig. 8, parts being shown in section;

Fig. 10 is a side elevation of the selector cup, being viewed from line 10—10 of Fig. 8;

Fig. 11 is a cross section taken on line 11—11 of Fig. 2; and

Fig. 12 is a detail plan view of a rotor viewed from the right in Fig. 2.

Similar reference characters indicate corresponding parts throughout the several views of the drawings.

The invention is applicable to all rotary ammunition, including that for 20 mm. to 16" diameter guns, rifled mortars, rotating rockets, etc. The fuze is point detonating, and is to be used in connection with ammunition that is also base detonating and is provided with means for selectively determining point or base detonation.

Referring now more particularly to Fig. 1, at numeral 1 is shown a tapered fuze body or head having a threaded shank 3 for application to the threaded end of a shell, rocket or the like suggested by the dotted lines. The shell or the equivalent, as is usual, carries the main explosive charge to be detonated by the fuze, and it also carries a booster charge directly behind the shank 3. It is this booster charge that the detonator charge of the present fuze sets off. The shank 3 is hollow and is interiorly threaded to receive a threaded retainer 5. This retainer has spanner sockets 7 with which a spanner wrench may cooperate for threading the retainer to its seat. Through the retainer is located a central

passage 9 for transmitting to the booster charge the effect of the detonator charge when fired in the fuze. At the forward end of this passage 9 the retainer 5 is formed as a spherical seat 11 for seating a spherical safety rotor 13.

The rotor 13 has a bore 15 along an axis which

passes through its spherical center. This bore consists in the short, small-diameter bore portion 17, and a larger main bore portion 19 filled with a sensitive detonating charge 20. At the end of the bore 19 is a short circular recess 21 which forms a shoulder within which seats one end of a selector pin 23. The pin 23 has a sliding fit in an angular bore 25, which extends outward from a counterbore 27 of the body 1, the counterbore 27 being located ahead of the retainer 5. The bottom of this counterbore 27 is conical as indicated at 29, the dimensions being such that when the rotor 13 is unlocked, it may freely rotate in the space thus provided for it but without undue looseness.

As indicated in Fig. 12, the rotor 13 carries recesses 31 at 120° intervals on a circular belt which is spaced from the central recess 21. Any one of the recesses 31 may be positioned on the longitudinal axis of the fuze when the selector pin 23 interlocks with the recess 21. A number of recesses 31 are used at equal intervals in order to effect required rotary balance around the axis of the bore 13. Each recess 31 has a beveled edge for cooperation with the beveled end 33 of a safety sleeve 35. This safety sleeve slides in the rear cylindric part 37 of an axial bore 39. The front end of the safety sleeve is flush with the rear elements of two coaxial crossbores 41 which intersect the axial bore 39 at 90°. Each crossbore 41 carries a cylindric detent slide 43. The slides 43 are encircled and normally held inward by a circular arming spring 45. This spring seats in a peripheral groove 47 cut into the body 1 in a position to intersect the outer ends of the crossbores 41. A pin 48 is staked into a hole 46 drilled into the groove 47 at 90° to the axes of the detent slides 43 (Fig. 3). The ends of the spring 45 are held adjacent to the pin 48 so that the spring exerts equal thrust on both detent slides 43.

The inner ends of the detent slides 43, by means of peripheral grooves 49, are formed with beveled undercut heads 51. These heads 51 between them accommodate the shank of a firing pin 53. This firing pin at the front end has a flat circular head 55 undercut as indicated at 57 for cooperation with the undercut heads 51 of the detent slides 43. The rear end of the firing pin 53 is pointed as indicated at 59, the length of the pin being such that its point under safety conditions lies within the safety sleeve 35 (Fig. 1). Thus the point 59 is normally completely protected from damage, and, as will appear, it per se does not release the rotor, this function being reserved for the safety sleeve 35.

The forward portion 61 of the axial bore 39 is tapered outwardly toward the pointed nose of the body 1, the taper preferably starting at the center line of the crossbore 41. For example, on one size of fuze, the portion of the bore 61 adjacent said center line may be made .25 inch in diameter and tapered .006 inch per inch of length larger on the diameter passing forward. The largest diameter is forward at which is a counterbored recess 63, open at the front.

Within the tapered bore 61 is a hollow striker 65, which is open at its rear end adjacent to the head 55 and closed at the front end, as indicated at 67. With the rear end against the head 55, the front end 67 lies in said enlarged recess 63 but at some distance away from the outer edge 69 of said recess. The striker is relatively light, being hollow and made with thin walls. Since there is more metal at the closed end 67

than at the rear open end, the center of gravity of the striker 65 lies forwardly with respect to a central point along its length. This fact, and particularly the fact of the tapered portion 61 of the bore 39, are of importance, as will appear in the description of operation.

Referring again to the passage 25 for the selector pin 23, it will be seen that towards its outer end it has an enlarged counterbore 71, traversed by a slot 73 (Figs. 3 and 7). The counterbore receives a selector cup 75, the latter being detailed in Figs. 8, 9 and 10. This cup comprises a flat top 77 in which is a slot 79 for accommodating a selector or setting tool such as a screw driver or the like. Extending from the top 77 is a skirt 81, one side of which is bulged as shown at 83. The purpose of this bulge is to provide means for a light, force-fit between the selector cup 75 and the counterbore 71. This fit is tight enough to hold the selector cup in any position into which it may be turned but free enough to permit it to be rotated by a tool (like a screw driver) in the slot 79.

On another side of the skirt 81 is a helical slot 85. This slot accommodates a selector guide pin 87. Pin 87 is fixed in an opening 89 in the selector pin 23, and extends through said slot 85 in cup 75 and into the slot 73 in the body 1. Thus, although the selector cup is rotary, the pin 23 is not rotary but is movable axially in the bore 25. The result is that by turning the cup 75 against the force of its tight fit, it is possible to move the selector pin 23 from the locking or unarmed position shown in Fig. 1 to the unlocking or armed position shown in Fig. 2. In the former position of Fig. 1 it positively locks the rotor 13 so that it will not be point detonated, even when the ammunition is fired. Under such conditions the projectile can only be base detonated, with some delay upon impact. When in the unlocking position of Fig. 2 the rotor is free, so far as is concerned the pin 23, and when the ammunition is fired will become automatically armed according to the operation to be described.

In order hermetically to seal the fuze, a sheath or cover 91 of this invention is employed, made for example of thin aluminum. This has a front impact diaphragm 93 which covers the opening 63 and a rear skirt 95 which is clinched over the base of the body 1 as shown in Figs. 1 and 2. This clinched portion 95 is then held hermetically by the adjacent parts of the shell when the shank 3 is screwed into position. An auxiliary seat 97 is used further to assure a seal at the end of the shell. This is similar to the showing in said application. A suitable additional gasket may be employed if desired.

It will be seen that since the sheath or cover is also over the opening 71, means needs to be provided for reaching the selector cup 75 with the setting tool. This is accomplished by indenting or pressing thin a suitable region of the sheath or cover 91 which will be located over the cup 75 at target 99. The indenting operation is such as to provide a circular bead or ridge 101 which serves as a locator for applying, say, a screw driver. Within the bead 101 the material of the cover 91 is pressed or indented to a breakable thinness, approaching that of foil, as indicated at 103. However, it is made only thin enough that it may easily be broken by means of the setting tool but not thin enough that it will be easily broken in shipment. Across the central portion of this diaphragm 103 is formed a guide

depression 105 which is parallel to the position of the slot 79 when the selector cup 75 is set into its locking position, as illustrated in Figs. 1 and 5. This position is crosswise of the axis of the projectile as a whole. For convenience, index characters of "Off" and "S. Q." are set at 90° intervals around the target 99, indicating two alternative settings. The index "Off" is opposite one end of the depression 105 and means that point detonation will not occur, but instead base detonation if the projectile is equipped for it. The index "S. Q." means super-quick, or point detonation.

The fuze is assembled as shown in Fig. 1, wherein it is statically safe. This is because the rotor 13 is positively locked by the selector pin 23 and by the safety pin 35. There is no conceivable practical condition of handling the projectile on which the fuze is located which would cause the rotor to turn into its armed position. Furthermore, since the entire fuze is hermetically sealed, it will remain in operating condition indefinitely since no moisture can enter to initiate corrosion of the parts or to accelerate deterioration of the detonator.

If the ammunition is to be fired for base detonation, that is, slightly delayed action at the target, nothing at all is done to the selector cup adjustment, the portion 103 being left untouched at the "Off" setting.

If it is desired to render the fuze point detonating prior to firing, a screw driver or the like is applied to the groove 105 and punched in through the embossing 103, whereupon it will enter the aligned slots 79 in cup 75. A quarter turn clockwise to the "S. Q." position of the selector cup will then cause the groove 85 to pull up the selector guide pin 87. This pin being in the slot 73 prevents the selector pin 23 from rotating but withdraws it from the counter-bore 21. Rotation of the screw driver proceeds easily because the material 103 will tear upon rotation. Since the cup 75 has a tight frictional fit in the opening 71, it will retain the super-quick (S. Q.) adjustment in which the rotor is released for subsequent arming. Nevertheless the projectile is still safe because of the locking action on the rotor 13 of the still locked safety sleeve 35.

Operation of the firing mechanism of the fuze is described in detail in the parent application Serial No. 592,131.

The invention provides a hermetically-sealed sheath or cover for a construction adapted selectively to be set one way or another on the inside, which may be reached by a hermetically sealing but frangible portion on said cover. The fuze is absolutely foolproof until set, and then it is very bore safe.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

A point-detonating fuze for a projectile comprising a generally conical fuze body having means at its base for attaching the fuze to the front of a projectile, an opening at the point of the fuze body and point-detonating fuze mechanism within said body adapted for impact actuation through said opening, a tool-operated adjustable mechanism within the body accessible through an opening in the side of the body, and a hermetically-sealing metal sheath clinched over the rear of the fuze body and covering said body including the openings at the front and side, the portion of the sheath that covers the point-detonating mechanism being of such thickness as to permit impact actuation of the mechanism through the opening, and the portion of the sheath that covers the adjustable mechanism being formed as an integral indented portion of such reduced thickness as to allow for its puncture by a tool for manipulating the adjustable mechanism.

PARKE H. THOMPSON.
